UNITED STATES PATENT OFFICE.

WILLIAM G. RESTORFF, OF WASHINGTON, DISTRICT OF COLUMBIA, ASSIGNOR OF ONE-HALF TO MARTIN McDONALD, OF WASHINGTON, DISTRICT OF COLUMBIA.

COMBINED VANITY-BOX AND PROGRAM.

1,156,815.

Specification of Letters Patent.

Patented Oct. 12, 1915.

Application filed March 18, 1914. Serial No. 825,629.

To all whom it may concern:

Be it known that I, WILLIAM G. RESTORFF, citizen of the United States, residing at Washington, in the District of Columbia, have invented certain new and useful Improvements in Combined Vanity-Boxes and Programs, of which the following is a specification.

This invention has as its object to provide an ornamental and useful article of jewelry designed especially to be worn at dances, dinners and other social functions, and which will be adapted for use as a vanity box, a container for candy mints and other like confections, and as a program, memorandum pad, menu and the like.

It is one aim of the invention to provide an article, such as above briefly described, in which the several parts will be so combined and so relatively arranged that the article as a whole will be compact and attractive in appearance, and so that the use of one part will not interfere with the use of another.

As stated above, the article is adapted to serve as a vanity box, as a container for confections, and as a program, and the invention has as a further aim to disclose a novel manner of hingedly mounting the lid of the vanity box, the lid of the confection container, and the cover of the program, the arrangement being such that the wall of the confection container will serve as a connection for both of said lids and the said cover. In this connection, a further aim of the invention is to not only make use of the edge portion of one wall of the confection container as a hinge support for the lid of the said container and the lid of the vanity box, but to further so form this edge portion that it will serve as a stop to limit the opening movement of the said lid of the vanity box and will conceal the spring which serves to automatically open this lid when released.

A further aim of the invention is to provide, in an article of this class including containers arranged in juxtaposition, means upon the lid of one of the containers for holding a small card or slip which may contain advertising matter, or the name of the society or the like giving the entertainment, or, in fact, any other desired data.

In the accompanying drawings: Figure 1 is a perspective view of the article embodying the present invention. Fig. 2 is a vertical front to rear sectional view there-

through. Fig. 3 is a group perspective view illustrating the confection container and the construction and arrangement of the lid for this container, the lid for the vanity box, and the cover for the program. Fig. 4 is a view in front elevation of a portion of the article, a part being shown in section. Fig. 5 is a plan view looking at the upper end of the article. Fig. 6 is a view similar to Fig. 2, illustrating a slight modification of the invention.

Corresponding and like parts are referred to in the following description and indicated in all the views of the accompanying drawings by the same reference characters.

The article comprises a back which is indicated by the numeral 1 and which may be of card board or of light metal, or, in fact, of any suitable material, and may have any desired ornamental outline and be finished or ornamented in any desired manner. The back 1 is formed with an opening 2 which receives the backs of the vanity box and confection container in a manner which will be presently pointed out. Reference may be made, however, at this point, to Fig. 2 of the drawings, in which the said box and container are illustrated as arranged within the opening 2, a sheet 3 of paper or other suitable material being pasted or otherwise applied to the back 1 so as to maintain the said box and container in proper position within the opening. At this point it may also be noted that a strip 4 is secured to the face of the sheet 3 and supports an attaching pin 5, the back of which is secured to the said strip. This pin also includes the usual piercing bar 6, which extends from a coil at one end of the back and at its pointed end is engageable with a keeper 7 located at the other end of the said back. This pin, of course, is employed for the purpose of attaching the article to the dress or coat of the user, and it will be obvious that if desired any equivalent attaching means may be provided.

The vanity box comprises a back 8, sides 9, a top 10, and a bottom 11, the box being closed by a lid 12, which constitutes the front thereof and which will be presently more specifically described. The confection container, heretofore referred to, comprises a back 13, sides or ends 14, a top 15, and a bottom 16. The confection container and vanity box are both of the same width and depth, and as illustrated clearly in Figs. 1

and 2 of the drawings, the box and container are so assembled that the bottom 11 of the box will rest against the top 15 of the container, the backs of the box and container occupying the same vertical plane, as also their open fronts.

As best shown in Fig. 2 of the drawings, the box and container are arranged within the opening 2 so that their backs will be substantially flush with the rear face of the back 1 of the article and the box and container are of such dimensions that they will fill the opening and fit snugly therein. The lid 12 of the vanity box is provided upon its outer face with a mirror 17, and the said lid at its lower edge, and more specifically, at each lower corner, is provided with a pintle lug 18. The top 15 of the confection container has its edge portion cut and bent to form spaced pintle lugs 19 of which there are a pair, these lugs projecting upwardly and slightly above the plane of the said top. The lid of the confection container is indicated by the numeral 20, and in that form of the invention shown in Figs. 1 to 5 inclusive, this lid is provided at its upper edge with a pair of spaced pintle lugs 21. The lugs 18, 19 and 21 are so relatively arranged that when the lids 12 and 20 are assembled with the top 15 of the confection container, the pintle lugs 21 will fit between the respective lugs 18 and 19. With the parts so assembled, a pintle pin 22 is fitted through the said lugs, and in this manner the lids 12 and 20 are hingedly connected with the confection container, and may be swung independently of each other, it being understood that the lid 12 is to be swung downwardly to open position and that the lid 20 is to be swung upwardly to such position. The lid 12 is held closed by means of a leaf spring catch 23, the shank portion of which is preferably secured between the sheet 3 and the back 8 of the vanity box, and this catch at its engaging end is curved upon itself to form a rounded end 24 beneath which the upper edge of the cover 12 may ride as the cover is moved to closed position. In order that the catch may be moved out of engaging position, and for a further purpose to be presently explained, the head 24 is provided with a relatively small knob 25 which projects forwardly therefrom. As before stated, a spring is provided for automatically moving the lid 12 to open position when released for such movement, and this spring is indicated in the drawing by the numeral 26 and is coiled about that portion of the pintle 22 which extends between the pintle lugs 19, one end 27 of the spring bearing against the bottom 11 of the vanity box and the other end 28 bearing against the inner face of the lid 12.

For the purpose of concealing the coiled portion of the spring, and further to pro-

vide means for limiting the opening movement of the lid 12, the portion of the top 15 of the confection container located between the lugs 19 is bent to approximately semi-circular form so as to provide an open sleeve 29, which extends upwardly in front of and conceals the spring 26, as stated, and has its upper edge so located that when the lid 12 is swung downwardly, it will strike the said edge of the sleeve and have its movement in this direction limited. As a means for preventing the powder within the vanity box sifting below the lower edge of the lid 12, a small baffle member comprising an inclined front 30 and ends 31 is arranged within the box upon the bottom 11 thereof, and with its said ends 31 resting against the back of the box and its front spaced from the said back of the box and located close to the said lid 12. A small powder puff 32 is arranged within the box and preferably rests partly within the said baffle member, as shown in Fig. 2.

Returning now to a further consideration of the lid 20 of the confection container, it will be observed that the upper edge portion of the lid, outwardly of the pintle lugs 21, is struck up to form relatively short flanges 33 and the lower edge of the said lid is, in a like manner, struck up to form flanges 34, the outer ends of which terminate at the end edges of the lid and the inner ends of which are located relatively close together, the said edge portion of the lid between the said inner ends of the flanges 34 being bent to form an angularly extending resilient latch tongue 35 provided with a small opening 36. In a like manner one end edge of the lid is struck up to form a flange 37 and by reference to Figs. 1 and 2, it will be apparent that a small card or slip 38 may be fitted beneath the overhanging portions of the flanges 33, 34 and 37, this card or slip having printed or marked thereon the name of the society or club or the like giving the dance or dinner, or, if desired, the card may contain some other printed or written information. In order that the sleeve 29 may not interfere with the swinging movement of the lid 20 to open position, the upper edge of the lid is cut away, as indicated at 39, to an extent sufficient to clear the said sleeve. The bottom 16 of the confection container is formed with pintle lugs 40 which, in the form of the invention shown in Figs. 1 to 5 inclusive, are three in number, and the cover of the program, indicated by the numeral 41, is formed at its upper edge with a pair of spaced pintle lugs 42 designed to be received between the lugs 40 in the manner shown in Fig. 4, a pintle pin 43 being fitted through the said lugs 40 and 42, whereby to hingedly connect the said cover with the said bottom of the container. A keeper lug 44 is provided upon the intermediate one of the lugs 130

40 and is designed for coöperation with the latch tongue 35 to hold the lid 20 in closed position.

As will be apparent by reference to Figs. 5 1 and 2 of the drawings, the back 1 constitutes the back of the program, the program pad being indicated by the numeral 45 and being secured in any suitable manner to the face of the said back below the confection 10 container. The cover 41 for the program depends from its hinged upper end and covers the pad 45 in the manner shown in the said figures, and in order that the cover may be held closed, a leaf spring catch 46 is se- 15 cured in any suitable manner at the lower end of the back 1 and has its latching end overturned to form a rounded head 47, over which the lower edge of the cover rides as the cover is swung to closed position. In 20 order that the cover may be held in open position, it is formed with an opening 48 so located that when the cover is swung open, the opening will receive the knob 25 upon the catch 23. The catch 46 preferably car- 25 ries an eye 49 to which may be attached one end of a cord or chain 50, the other end thereof being secured to a pencil 51 remov- 30 ably fitted in clips 52 upon the back 1. In that form of the invention shown in Fig. 6 of the drawings, the hinge arrangement illustrated in Fig. 3 is reversed and the keeper stud 44 indicated in the said Fig. 6 by the numeral 44^a is carried by the sleeve 29, the lid 20, in the said Fig. 6, being 35 hinged at its lower edge and being, therefore, adapted to be swung downwardly to open position.

If desired, instead of employing the at- 40 taching pin 5, a ribbon 52' may be threaded through openings 53 in the back 1 at the upper end thereof and may be tied in any suitable manner.

Having thus described the invention, what is claimed as new is:

45 1. In an article of the class described, a back, containers supported by the back in juxtaposition to each other, a pad upon the back adjacent one of said containers, and a lid for each container and a cover for the 50 pad, the lids and cover being hingedly connected with the walls of one of said containers.

2. In an article of the class described, containers supported in juxtaposition to each 55 other, a pad supported adjacent one of said containers, and a lid for each container and a cover for the pad, the lids being hingedly connected with one wall of one of the containers and the cover for the pad being 60 hingedly connected with the opposite wall of the said container.

3. In an article of the class described, containers supported in juxtaposition to each other, a lid for each container, the said lids 65 and one wall of one of the containers being

provided with interfitting pintle lugs, a pintle pin passed through said lugs and hingedly connecting the said lids with the said wall, a pad, and a cover for the pad hingedly connected to the opposite wall of the 70 said container.

4. In an article of the class described, containers supported in juxtaposition to each other, one of said containers being provided upon one wall with spaced pintle lugs, a lid 75 for the other container provided at one end with spaced pintle lugs, a lid for the first-mentioned container provided with spaced pintle lugs fitting between the lugs upon the said wall of the container and the lugs of the first-mentioned lid, a pintle pin fitted through the lugs, and means upon the said wall of the said first-mentioned container for limiting the opening movement of the lid 80 of the second-mentioned container.

5. In an article of the class described, containers supported in juxtaposition to each other, one of said containers being provided upon one wall with spaced pintle lugs, a lid 85 for the other container provided at one end with spaced pintle lugs, a lid for the first-mentioned container provided with spaced pintle lugs fitting between the lugs upon the said wall of the container and the lugs of the first-mentioned lid, a pintle pin fitted 90 through the lugs, a spring upon the pintle pin between the lugs upon the container arranged to swing the lid for the second-mentioned container to open position, and a guard upon the said wall of the first-mentioned container extending across the space 95 between the said lugs upon the said wall and constituting a guard for the said spring.

6. In an article of the class described, containers supported in juxtaposition to each other, one wall of one of the containers being provided with spaced pintle lugs, a lid for each container, each lid being provided with pintle lugs, and the pintle lugs of the 105 lids and upon the said wall being interfitted, a pintle pin passed through the said lugs, a spring upon the pin between the first-mentioned lugs arranged to move the lid upon the other container to open position, and a portion projecting from the said wall of the 110 first-mentioned container between the said first-mentioned lugs and extending upwardly and partly embracing said spring and con- 115 cealing the same, the end of said portion constituting a stop to limit the opening movement of the said lid upon the second-mentioned container.

7. In an article of the class described, containers supported in juxtaposition to each other, a pad, a cover for the pad hingedly 120 connected with one of the containers, a lid for the other container, a catch for holding said lid closed, and coöperating means upon the said catch and cover for holding the cover in open position.

8. In an article of the class described, containers supported in juxtaposition to each other, a pad supported adjacent one of said containers, a lid for the said container hingedly connected to one wall thereof, a cover for the pad hingedly connected to the other wall of the said container, the hinge connection including a pintle lug, a catch upon the lid, a keeper upon the said pintle lug, and a lid for the other container hinged to the first-mentioned wall of the first-mentioned container.

9. In an article of the class described, a container having an open front, a hinged lid for closing said front, and a baffle member including a front and ends, the said member being disposed within the container upon the bottom thereof and having its ends resting against the back of the container.

10. In an article of the class described, containers supported in juxtaposition to

each other, a lid for one of the containers hinged to one wall of the other container, a lid for the other container also hinged to the said wall, means for holding the lids closed, 25 and card holding flanges at the upper and lower edges and one end edge of the second-mentioned lid.

11. In an article of the class described, a container, a pad adjacent the said container, 30 a lid for the container hinged to one wall of the container and a cover for the pad, and means for holding the lid in closed position arranged also to hold the cover in open position.

In testimony whereof I affix my signature in presence of two witnesses.

WILLIAM G. RESTORFF. [L.S.]
